ATTORNEYS

REINHOLD HANSFELD, a non-resident of the United States, residing in Berlin, Germany, and FREDERICK W. HANNA, a non-resident of the United States, residing in Berlin, Germany, both citizens of the Federal Republic of Germany, have invented a new and useful improvement in combined chair and table, as described in the drawings and particularly set forth in the claims hereinafter set forth.

This invention relates to a combined chair and table for small children and especially to that class of such articles wherein the chair may be set into the table, leaving a table-top around the chair for use of the child seated in the chair or the chair may be lifted out and the table-top closed to form a complete table for card-playing or other uses.

UNITED STATES PATENT OFFICE

2,566,081

COMBINED CHAIR AND TABLE

Baldwin L. De Korne, Denver, Colo.

Application July 28, 1947, Serial No. 764,109

3 Claims. (Cl. 155—123)

1

This invention relates to combined chair and table for small children and especially to that class of such articles wherein the chair may be set into the table, leaving a table-top around the chair for use of the child seated in the chair or the chair may be lifted out and the table-top closed to form a complete table for card-playing or other uses.

An object of the invention is to provide a child's seat within a table-top which holds the child securely in the seat without restricting the normal movements of the child while using the table-top around the chair.

A further object is to provide an article of the class described and which shall accomplish the objects above stated by the use of straight-lined, smooth-surfaced rigid elements, thus eliminating belt buckles, catches and folding or collapsible members and increasing the security of the child in the seat and, coincidentally, minimizing the danger of injury to the child from snagging, scratching or pinching by contact with such elements or members and likewise the danger of injury from accidental collapse.

A further object is to provide an article of the class described which shall have only smooth surfaces and all parts of which shall be easily accessible for cleaning.

With the above and other objects in view, all of which shall more fully appear in the following description, the invention comprises certain novel constructions, combinations and arrangements of parts as will now be described and defined in the appended claims and illustrated in the accompanying drawing in which:

Figure 1 is a plan of the combined chair and table, elements beneath the table-top being indicated in broken lines.

Figure 2 is a view on line 2—2 of Fig. 1.

Figure 3 is a front elevation of the combined chair and table, a plan of which is shown at Fig. 1.

Figure 4 is a fragmentary section on line 4—4 of Fig. 1, and

Figure 5 is a front elevation of the chair, separated from the table.

The invention comprises a table and a chair. The table may be of any ordinary construction except that portion thereof which functions as a receptacle or socket for the chair and which will be later described. The table is preferably supported by legs 6 with casters 7, a surrounding apron 8 and a top 9, which may be of thin material as the chair is supported otherwise than by the top. A portion of the top is cut away to permit the insertion of the chair, the lines 10, 11 and

12 indicating the edges of the top 9 which define the cut-out portion. Beneath the portion of the top adjacent edges 10 and 11, I provide members 13 and along the inside of the members 13 I provide supporting and seating beams 14 extending opposite aprons 8 and having their ends supportingly secured to said aprons by any suitable means as nails, screws, etc., not shown.

The upper rear portions of beams 14 are cut away from a point coincident with edge 12 of the top, thence inclined forwardly as at 15, to a depth sufficient to accommodate the chair arm hereafter described, thence horizontally along line 16 to the rear end of the beam, all as clearly shown at Fig. 2. A shelf, indicated by the line 16 is thus provided along and below the edges 10 and 11 of the cutaway portion of top 9.

The chair comprises a seat 17 having a back 18, side boards 19 and arms 20 secured to and along the top edges of side boards 19 and projecting laterally therefrom. The chair is made of a width adapted for an easy sliding fit of side boards 19 between beams 14 so that arms 20 will seat on shelves 16. The forward ends of the arms are inclined to co-mate with inclined cuts 15 in beams 14 and the arms are of the same height as the distance from shelves 16 to the top surface of top 9 so that when the chair is slid down between beams 14 until the arms rest on shelves 16 and then the arms are slid forward on the shelves until their forward inclined ends co-mate with cut 15, the top of the arms will be co-planar with the upper surface of top 9 and the edges of the arms will closely mate with edges 10, 11 and 12 of the top.

To hold the chair securely in its last described position, I provide block 21 of length slightly less than the distance between the inner or opposed faces of members 13, of width sufficient to wedge the chair in above described forward position when the block is inserted between the back of the chair and the rear apron 8 as clearly shown at Fig. 2. The block is preferably of a thickness to reach from shelves 16 to the underside of top 9 and a piece 9a of the same material as top 9 is secured to the top of the block covering the same and overlapping the top edge of the apron and thus providing a continuation of top 9 behind the chair when seated in the table, moved forward and blocked as above described.

The chair is also provided with a foot-rest 22 carried between the lower ends of sideboards 19 and a leg-separating member 23 secured to the foot-rest and to the forward edge of seat 17 as clearly shown at Figs. 2, 3 and 5.

The structure illustrated and described obviously accomplishes the object heretofore stated.

I have illustrated and described many details of construction but I am not to be limited to such details as alternatives and equivalents will be obvious to those skilled in the art and are within the scope and spirit of the appended claims.

I claim:

1. A combination chair and table comprising a solid table top having an orifice therein with two parallel sides, shelves below said sides, a chair adapted to be positioned in said orifice and elongated arm members on the sides of the chair adapted to seat on and parallel with said shelves with their tops co-planar with the upper surface of said table top, the chair member having a back which projects above the table top when the arms are seated on the shelves, stops carried at the forward ends of said shelves, the forward ends of the arms being adapted to interlock with said stops and thereby hold the back of the chair at a predetermined distance from the forward edge of the orifice and adapted also to prevent upward movement of the forward ends of the arms.

2. A combination chair and table comprising a solid table top having an orifice therein with two parallel sides, shelves below said sides, a chair adapted to be positioned in said orifice and elongated arm members on the sides of the chair adapted to seat on and parallel with said shelves with their tops co-planar with the upper surface of said table top, the chair member having a back which projects above the table top when the arms are seated on the shelves, stops carried at the forward ends of said shelves, the forward ends of

the arms being adapted to interlock with said stops and thereby hold the back of the chair at a pre-determined distance from the forward edge of the orifice and adapted also to prevent upward movement of the forward ends of the arms, and a removable block adapted to seat between the back of the chair and the rear edge of the orifice and thereby hold the chair in forward position in the orifice and to hold said arms and stops in interlocked relationship.

10 steps in interlocked relationship.

3. A combination chair and table including a table top having an orifice therein but otherwise solid, said orifice having two parallel sides, shelves parallel with said sides and below the top surface of the table top, a chair having elongated arms adapted to slidably seat on said shelves with their tops co-planar with the top surface of the table top, said orifice and shelves being adapted to receive said chair while in its normal, substantially upright, position with its arms maintained in parallelism with said shelves.
